UNITED STATES PATENT OFFICE.

CHARLES MONDENG, OF MINNEAPOLIS, MINNESOTA.

HONEY-BOX MACHINE.

SPECIFICATION forming part of Letters Patent No. 629,167, dated July 18, 1899.

Application filed March 25, 1898. Serial No. 675,088. (No model.)

To all whom it may concern:

Be it known that I, CHARLES MONDENG, a citizen of the United States, residing at Minneapolis, in the county of Hennepin and State of Minnesota, have invented certain new and useful Improvements in Honey-Box Machines; and I do hereby declare the following to be a full, clear, and exact description of the invention, such as will enable others skilled in the art to which it appertains to make and use the same.

My invention relates to machines for making honey boxes or sections; and it has for its principal object to provide such a machine capable of performing the complete operation and making the box blank or section.

My invention consists of the novel devices and combinations of devices hereinafter described, and defined in the claims.

The preferred form of my said invention is illustrated in the accompanying drawings, wherein like characters indicate like parts throughout the several views.

Figure 1 is a view in right side elevation showing my improved machine. Fig. 2 is a plan view of the same. Fig. 3 is a vertical section taken approximately on the line $x^3 x^3$ of Fig. 2. Fig. 4 is a detail view in rear elevation with some parts broken away, showing the discharge-plunger or ejecting-blade and associated parts. Figs. 5 and 6 are diagram views, respectively, in right and left side elevations, illustrating in particular the driving connections for the various movable parts of the machine; and Figs. 7 and 8 are perspective views of the finished product, the former showing the section as in blank form and the latter illustrating the completed box.

The frame of the machine is made up principally of a flat bed-plate a and parallel side brackets a' , which support the same. A rectangular channel through which the blanks are fed laterally is formed on the face of the bed-plate a by the co-operation of a fixed longitudinally end guide b , an adjustable longitudinally-extended end guide b' and a pair of overhead or top guide bars or strips b^2 . The adjustable guide b' is provided with slotted feet or lugs b^3 , through the slots of which set screws b^4 are passed and screwed into the bed-plate a .

The overhead guides or bars b^2 are provided with forward extensions b^5 , that are provided with perforations b^6 . Spring-catches b^7 are secured to the forward end of these extensions b^5 and work with their free ends mounted for vertical movements within said perforations b^6 . Immediately below each of these springs or catches b^7 is a coöperating and similar spring-catch b^8 . These spring-catches b^8 are shown as countersunk into the bed-plate a , to which their forward ends are secured, and are provided with depending fingers at their free ends, which are free to work in seats or perforations b^9 in said bed-plate.

The blanks are fed laterally, extending transversely of the machine and setting edge-wise in a vertical plane, by means of a reciprocating feed-head. As shown, this feed-head comprises a transverse angle-bar c , provided with end flanges c' and longitudinally-extended racks c^2 , which latter work in suitable guide-slots c^2 cut in the bed-plate a . Pinions c^3 , carried by a transverse rock-shaft c^4 , mounted in the sides a' , are in mesh one with each of said racks c^2 . One end flange c' of the feed-head—as shown the right-hand member—is provided with a depending finger c^5 , which is spaced apart from the face of the feed-bar c far enough to permit the blank to be placed between the same by endwise movement.

At the rear end of the blank-containing channel or guideway, hereinbefore noted as being formed between the bed-plate a , bars b^2 , and end guides b b' , a discharge-head or ejector is mounted to work vertically, so as to eject the sections one by one. This discharge-head or ejector, as shown, comprises a transversely-extended ejector-blade f , set edgewise in a vertical plane and provided at its ends with vertical racks f' . The ejector-blade f works in a narrow transverse exit-passage f^2 , formed between the rear end of the blank-containing channel and the face of a guide flange or plate f^3 , that is rigidly secured at its ends to the frame sides a' . Pinions f^4 on a rock-shaft f^5 , journaled in boxes f^6 on the main frame, are in mesh one with each of the racks f' .

The feed-head and the discharge-head or ejector are reciprocated so that the former will feed and the latter discharge or eject a

section in alternate order through the following connections: The shaft f^5 is provided with an arm f^7 , and the shaft c^4 is provided with a bell-crank c^6 . The lower arm of the bell-crank c^6 is connected to the free end of the arm f^7 by a link f^8 . c^7 indicates a counter-shaft which is journaled in the lower portions of the side frames a' . This shaft c^7 is provided at one end with a crank-arm c^8 , which is connected to the upper arm of the bell-crank c^6 by means of a link c^9 . The shaft c^7 is also provided with a pulley c^{10} .

A shaft g , mounted in suitable bearings on the under side of the bed-plate a , carries a circle-saw g' , that is arranged to cut in a plane extending in line with the inner surface of the end guide b and at a point just rearward of the position normally occupied by the feed-head. At its outer end the shaft g is provided with a small pulley g^2 . Transversely opposite to the saw g' the guide b' is cut away or notched on its inner guiding edge, as shown at b^{10} . After this notch b^{10} reaches a point rearward of the transverse line cutting the rear edge of the saw it is inclined or beveled, so that it will cam the sections back into the line which they formerly occupied.

The cutters for forming the notches or the entrance-grooves through which the bees pass, in the honey-boxes, are carried by a pair of parallel shafts h and h' , which, as shown, are located approximately at the middle of the machine and are positioned one directly over the other. The shaft h is mounted in journal-boxes h^2 , that are adjustably mounted for vertical movements on brackets h^3 , rigidly secured to and rising from the opposite sides of the bed-plate. The journal-boxes h^2 are vertically adjusted by means of vertical screw-rod h^4 , swiveled thereto and working through lugs h^5 on the brackets h^3 . At their upper ends the screw-rods h^4 are provided with sprocket-wheels h^6 , over which a sprocket-chain h^7 runs, so that both of said screw-rods, and hence, also, both of said journal-boxes h^2 , will be simultaneously moved or vertically adjusted. This simultaneous adjustment of the journal-boxes h^2 is readily accomplished by means of a hand-crank h^8 , secured or securable to one of the screw-rods h^4 . By this means it is evident that the shaft h when vertically adjusted will always remain parallel to the face of the bed-plate a .

The shaft h' is journaled in boxes or blocks h^9 , that are mounted for vertical adjustments in keepers or brackets h^{10} , secured to the under side of the bed-plate a , one at each side of the same. Set-screws h^{11} work through the bottoms of the keepers h^{10} and engage the bottoms of the blocks h^9 to effect the vertical adjustments of the same. Other set-screws h^{12} , which work through the sides of the brackets h^{10} and are screwed into the blocks h^9 , serve to lock said blocks wherever set.

The knives or cutters h^{13} , which cut the bee-passages or entrance-notches, are approximately U-shaped, and their prongs are se-

cured to annular heads h^{14} , that are adjustably mounted, two on the shaft h and two on the shaft h' . The upper cutters work through passages cut in the overhead guides b^2 , and the lower cutters work through similar passages cut in the bed-plate a .

Rigidly secured to the sides a' , beneath the bed-plate a and extending parallel to the counter-shafts h and h' , is a transverse guide-rod k .

Mounted for transverse adjustments on this rod k is a pair of journal-brackets k' , having journal-boxes k^2 , in which vertical counter-shafts k^3 are journaled. The lower ends of the brackets k' embrace the transverse guide-bar k^4 . The prongs which embrace this guide-bar k^4 are adapted to be clamped onto the same to rigidly secure the lower end of the bracket by means of set-screws k^5 . At their intermediate portions between the boxes k^2 the vertical counter-shafts k^3 are provided with small pulleys k^6 . The upper ends of the said shafts k^3 project upward through large transversely-extended slots k^7 , formed in the bed-plate a , and above the bed-plate a they are provided with a plurality or stack of small circle-saws k^8 , that are spaced apart from each other approximately the thickness of the saws themselves. The saws on the one shaft or spindle k^3 are set in planes that fall between the saws that are carried by the other shaft or mandrel. As will later appear, these saws are adapted to cut grooves in the ends of the box-section, or, in other words, to form the same with an interlocking tongue-and-groove joint.

The brackets k' , and hence, of course, the saws k^8 , are adapted to be adjusted laterally and to be moved outward far enough to throw said saws outward of the guides b and b' , thereby permitting the saws to be lifted off from their shafts or mandrels. As shown, the right-hand bracket k' is adjusted by a long transverse rod k^9 , that is swiveled against endwise movement in the left-hand bracket k' , works through a large perforation k^{10} in the left-hand bracket k' , and is screwed into said right-hand bracket. The left-hand bracket is in a similar manner adjusted by a short screw-threaded rod k^{11} , that is swiveled against endwise movement in the left-hand frame-section a' and is screwed into said left-hand bracket k' . A removable hand-crank k^{12} is adapted to be applied to the projecting angular ends of either of the screw-rods k^9 k^{10} .

Below the bed-plate a , between the saws k^8 and the discharge-passage f^2 , another transverse counter-shaft n is journaled. Said shaft is journaled directly in boxes n' , that are adjustably mounted in keepers or flanged seats n^2 and are secured where set by set-screws n^3 . At its outer end the counter-shaft n is provided with a small pulley n^4 , and at its intermediate portion it is provided with a series—as shown three—of tool-carrying heads or collars n^5 , that are preferably adjustably mounted on said shaft. These heads or collars n^5 carry knives n^6 , that are provided with

V-shaped extremities, adapted to cut V-shaped vertical grooves in the box-sections as they are being ejected or forced vertically downward against the face of the backing or guide-plate f^3 . The box-sections are spring-held 5 against the face of said backing or guide f^3 while the cutters n^6 are operating thereon by means of spring-fingers p , that are secured at their intermediate portions to a transverse 10 bar p' , rigidly secured to and extending between the frame brackets or sides a' .

The driving belts and pulleys which in the particular construction illustrated are employed to give motion to the various movable parts are illustrated in Figs. 5 and 6. In these views 1 indicates what for the purposes of this illustration may be described as a "wide-faced pulley," although, in fact, several pulleys will be employed instead. This pulley 1 is carried by a shaft 2, which may receive motion in any suitable way. The shaft 2 also carries a very small pulley 3. 4 indicates the counter-shaft, provided with a large pulley 5 and small pulley 6. A belt 7 runs over the pulleys 3 and 5, and another belt 8 runs over the pulley 6 and the pulley e^{10} , which latter pulley transmits motion to the feed-head and discharge-head or ejector. The parallel shafts h and h' project in opposite directions and 25 are provided at their projecting ends, respectively, with small pulleys h^{15} and h^{16} . A belt 9 runs over the pulley 1 and the pulley h^{16} . A belt 10 runs over the pulleys g^2 and n^4 . A belt 11 runs over the pulley 1, small pulley h^{15} , over the pulley g^2 and belt 10, and over a loose pulley 12. Belts 13 run over pulleys 1 and k^6 .

In the description of the operation, which will soon follow, it will be important to note 40 the action of a cam-flange or knife-edged strip t . This cam strip or knife t is shown as secured to the under side of the right-hand member of the overhead guides b^2 and at a point transversely opposite to the recessed or 45 cut-away portion b^{10} of the guide b' .

In Figs. 7 and 8, z indicates the finished box-section, which when finished is provided with three transversely-extended V-shaped grooves z' , that are cut nearly, but not quite, through 50 the section. At its ends said section z is formed with interlocking tongues and grooves z^2 , and certain of the subsections or sides of the box-forming section z are grooved or cut out, as shown at z^3 , to form what are usually 55 termed "bee-entrances." As shown in Fig. 8, the box, when formed for use, is rectangular, three of the corners being formed by folding the section at its V-shaped grooves z' and the fourth corner being formed by in- 60 terlocking the tongue-and-groove-formed ends.

Operation: As previously indicated, the so-called "sections" or "box-sections" z are formed from long strips that are already cut 65 to the proper thickness and width. These long strips are fed by hand through the narrow passage formed between the finger c^5 and

the face of the feed bar or head c , the strip being forced inward until it strikes the end guide b' . The section-forming strip must of course be thus forced into place while the feed-head c stands in its normal position. (Indicated in Fig. 1.) When said feed-head is reciprocated into the position indicated in Fig. 3, the strip will be forced by the cutting edge of the saw g' and the first box-section will be cut off. This same movement, it will be noted, carries the section thus cut off inward of the free ends of the spring-catches b^7 and b^8 , so that this section cannot return 70 with the feed-head. The finger c^5 on the feed-head will, however, carry the inner end of the section-forming strip forward of the saw, so that it may be readily moved into position to be again cut off on the next forward 75 movement of the feed-head. It is of course evident that every time a box-section is cut off under the forward movement of the feed-head the sections which have previously been cut off will be forced inward or forward in 80 the guide channel or magazine a distance equal to the thickness of said sections. By this process the said guide channel or magazine will be completely filled with box-sections. Immediately after the sections have 85 been cut off by the saw g' they will be thrown in contact with the knife-edged cam-flange t , and by it they will be forced endwise away from the saw and with their farther ends projected into the recess b^{10} of the end guide b' . 90 Then as they are forced onward to a point just beyond the saw g' the cam or incline b^{11} will force said sections back into the same line which they before occupied, with their right-hand ends against and guided by the 95 guide b . The sections z will next be forced between the cutters h^{18} , and the bee-entrances z^3 will be cut. After passing the cutters h^{18} the sections z will be forced between the tongue-and-groove-cutting saws g^8 and the 100 tongue-and-groove joints z^2 will be cut in the ends of said sections. The section z , which by the last succeeding feed movement of the feed plunger or head c was forced against the 105 backing or guide plate f^3 , will by the downward movement of the discharge-head or ejector be engaged by the ejector-blade f and forced downward through the exit slot or passage f^2 and will then be held against the 110 lower portion of said plate f^3 by the upper ends of the springs p . This downward movement of the ejector, it will be remembered, takes place simultaneously with the return or backward movement of the feed head or bar. The next succeeding section z , which is 115 forced downward by the ejector-blade f , will force the previously-ejected section out of 120 position and cause the same to drop. However, as these sections z are ejected, as above 125 described, they will be acted upon by the cutters n^6 , and the V-shaped corner-grooves z' will be thereby cut, so that when the sections are dropped from the machine, as just noted, 130 they are a finished product, or, in other words,

are completely-formed sections, as shown in Fig. 7, adapted to be folded to form the box shown in Fig. 8.

So far as I am aware I am the first to provide a single machine adapted to perform the complete operation of forming finished honey-box sections of the character shown from blank-strips.

While I have very specifically described the preferred form of my invention above illustrated, it will of course be understood that I do not limit myself to these details. On the contrary, it is obvious that my invention is capable of a large range of modification.

What I claim, and desire to secure by Letters Patent of the United States, is as follows:

1. The combination with a channel or guideway extended laterally and longitudinally in a horizontal plane, of a reciprocating feed-head operating to feed the blank-strips sidewise into said guideway, a discharge-head or ejector mounted to move vertically across said guideway to eject said strips edgewise, one at a time, connections for reciprocating said feed-head and ejector so as to feed and discharge alternately, and intermediate section-forming devices, operating substantially as described.
2. The combination with a channel or guideway extended laterally and longitudinally in a horizontal plane, of a feed device operating to feed the blank-sections sidewise into said guideway, a discharging device or ejector operating to eject said sections, one at a time, by edgewise movement in a vertical plane, stationary corner-groove-forming cutters positioned to operate on the sections as they are being ejected edgewise, and intermediate section-forming devices, operating substantially as described.
3. The combination with a channel or guideway for the sections and a feed device for delivering the sections thereto, of a saw arranged to cut at one side of said guideway, and the cam flange or rib t projecting into said guideway and arranged to engage the intermediate portions of said sections just after they are

cut by said saw and to cam the same endwise away from the saw, substantially as described.

4. The combination with a channel or guideway for the sections, and a feed device for delivering sections thereto, of a circle-saw arranged to cut in the plane of one side of said guideway, a recess formed transversely opposite to a portion of said saw, as at b^{10} , and terminating in the cam portion b^{11} , and the cam flange or rib t secured and projecting into said guideway for action on the sections, substantially as described.

5. A combination with a channel or guideway for the sections, of a reciprocating feed-head delivering sections sidewise thereto, a circle-saw arranged to cut off the sections presented thereto by said feed-head, cutters working through the top and bottom of said channel for forming the bee entrances or passages and the tongue-and-grooved corner-joint in said sections, while passing through said guideway, a discharge-head or ejector working transversely of said guideway and discharging said sections edgewise one at a time, and the cutters for forming the V-shaped corner-grooves in said sections as they are ejected or discharged, substantially as described.

6. In a machine for forming honey-boxes, the combination with a channel or guideway for the sections, of reciprocating feeding and discharging devices mounted to work in reverse order, a saw for cutting off the sections under the action of the said feed device, cutters for forming the bee-entrances, cutters for forming the tongue-and-grooved corner joints, and cutters for forming the V-shaped corner-grooves, all of the said parts being automatically operated with a properly-timed action and operating as a single machine to form a complete honey-box, substantially as described.

In testimony whereof I affix my signature in presence of two witnesses.

CHARLES MONDENG.
